(57) **CLAIM**

The ornamental design for a watch, as shown and described.

DESCRIPTION

FIG. 1 is a perspective view of a watch showing my new design;

FIG. 2 is a top plan view of FIG. 1;

FIG. 3 is a first end elevation view of FIG. 1, with the second/opposite end elevation view being in mirror image;

FIG. 4 is a right side elevation view of FIG. 1;

FIG. 5 is a left side elevation view of FIG. 1; and,

FIG. 6 is a bottom plan view FIG. 1.

The dotted lines show portions of the watch that form no part of the claimed design.
